UNITED STATES PATENT OFFICE.

GEORGE H. REYNOLDS, OF NEW YORK, N. Y., AND HERMAN HAUPT, OF PHILADELPHIA, PA.

IMPROVEMENT IN PNEUMATIC MOTORS.

Specification forming part of Letters Patent No. 222,950, dated December 23, 1879; application filed March 26, 1879.

To all whom it may concern:

Be it known that we, GEORGE H. REYNOLDS, of the city and State of New York, and HERMAN HAUPT, of the city and county of Philadelphia, in the State of Pennsylvania, have invented certain new and useful Improvements in Pneumatic Motors, of which the following is a full, clear, and exact description, reference being had to the accompanying drawings, forming part of the same.

This invention relates to the use of compressed air as a motive agent, and although applicable to motors for various purposes is more especially designed to be used for driving locomotive engines or carriages on tramways and other roads.

In the use of compressed air as a motive power for locomotive purposes it is desirable, on account of the limit of reservoir-capacity, to use the air at the highest practicable initial pressure.

The use of the air at such high pressure has been attended with great difficulties, one of which is the liability to congelation of moisture on the surfaces of the engine, resulting from the low temperature consequent upon the high rate of expansion.

Another difficulty results from the excessive pressure upon the valves, which renders them liable to cut; and a further one is that, owing to the necessity of cutting off very early in the stroke of the piston, the full initial pressure is exerted on the engine-crank only while it is in its least effective position—viz., when it is at or very near its dead-center.

The first-mentioned difficulty has been partially overcome by heating the air before introducing it to the engine-cylinder; but when this has been done an engine of the simple type has always been used.

The object of our invention is to further overcome the several difficulties above mentioned; and to this end we employ an engine of the compound type, and though we may or may not heat the air before its introduction to the engine we always heat it after its exhaust from the high-pressure cylinder and before its induction to the low-pressure cylinder; and to this end our invention consists in the com-

bination, with a compound engine for the use of compressed air for motive power, of a heater placed between its high and low pressure cylinders and containing heated water or other liquid, through or in contact with which the air passes between its ejection from the one cylinder and its induction into the other.

In the application of the invention to locomotives or locomotive-cars this heater may occupy any convenient position on or under the locomotive or car, and may be filled with hot water, or such other hot liquid as it may be desirable to use, from a stationary boiler or heater suitably placed at the terminus or other convenient place near the track.

In other applications of our invention the said heater may be supplied with heated water or other liquid in any convenient manner.

Referring to the accompanying drawings, Figure 1 represents a sectional plan of a compressed-air locomotive-engine in part having the invention applied, and Fig. 2 a transverse section thereof through the working cylinders of the engine.

A represents the framing of the locomotive, which may be of any suitable construction, and B B' its running and driving wheels. C is the smaller cylinder, and D the larger cylinder, of a compound engine used to propel the locomotive or carriage, and the pistons a b of which are respectively connected by suitable rods with cranks c d on the driving-shaft E.

G G are compressed-air reservoirs, of which there may be any suitable number carried by the locomotive, and which may be charged or recharged with compressed air under a high pressure at the termini or any intermediate places on the road. The air from these reservoirs is first conducted by pipes e to a heater, H, which may be termed a "high-pressure" heater, and from thence, by a pipe, f, to the high-pressure or smaller cylinder C of the compound engine, subject, of course, to the control of a suitable valve applied to said cylinder. After the air has performed its duty in the high-pressure cylinder C it is exhausted therefrom and passed, by a pipe, g, to a heater, H', which may be termed the "low-pressure" heater, and from whence it is passed, by a

pipe, *h*, to the valve-box of the larger or low-pressure cylinder *D*, there to do its duty by expansion, and ultimately escape to the atmosphere by a pipe, *i*.

The low-pressure heater *H*, which is the principal feature of the combination which constitutes our invention, may be of any suitable construction capable of sustaining the pressure due to the heat of the water or other liquid with which it is to be charged for the purpose of heating the air after it has been exhausted from the high-pressure cylinder *C*, and before its induction to the low-pressure cylinder *D*, and should have suitable provision afforded by its form or construction for the air introduced into it from the one cylinder to pass through or in extensive surface-contact with the hot water or other liquid contained therein before its advent to the low-pressure cylinder. The high-pressure heater may be of similar construction.

The air in passing through or in contact with the hot liquid in the heater *H'* may have its expansive force very considerably increased by the heat which it takes up from the liquid, while there is a very gradual reduction of the temperature. This is owing to the difference between the specific heat of the air and of the liquid. When the liquid used in the heater *H'* is water a very considerable increment of expansive force is obtained from the vapor which is taken up by and mixed with the air.

By means of the compound engine air at a very high pressure in the reservoir may be used without employing a reducer, and without much or any cutting of the valves, and without cutting off disadvantageously early in the stroke, by reason of the piston of the high-pressure cylinder being exposed on its exhaust

side to the working pressure of the air in the larger or low-pressure cylinder.

The number of heaters interposed between the cylinders may be varied, and, if desired, the air from the reservoirs may be passed direct from the latter to the first, or high-pressure, cylinder without circulating it through a heater; but it is preferred to use heaters for warming, expanding, and keeping up the pressure of the air in the transmission of it to the high-pressure cylinder as well as to the low-pressure cylinder, thus obtaining the advantage to be derived from heating of the air in both cylinders.

We are aware that heaters have been employed in compound steam-engines for heating the steam between the high and low pressure cylinders; but we make no claim for steam-engines.

We are also aware that compressed air has been heated before its introduction to an engine, and we therefore do not claim anything relating to such heating of the air; but

What we claim as our invention is—

The combination, with a compound engine for the use of compressed air as a motive power, of a heater, arranged between the high and low pressure cylinders of such engine, and containing heated water or other liquid, through or in direct contact with which the air passes on its way from the high-pressure to the low-pressure cylinder, substantially as and for the purpose herein described.
